UNITED STATES PATENT OFFICE

LEWIS J. BAZZONI, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY

MACHINE FOR USE IN COVERING HEELS

Application filed June 28, 1929. Serial No. 374,555.

This invention relates to machines for use in covering heels and is herein disclosed as embodied in an automatic machine capable of trimming edge portions of a partially applied heel cover and applying the trimmed edge portions to a heel by tucking them into channels provided in the heel for their reception; although it should be understood that the invention is not limited to an automatic machine nor, in respect to many of its features, to a machine capable of performing both of the stated operations.

In covering wooden heels a cemented cover of leather or other thin sheet material is drawn and stretched around the back and sides of a heel, to which the cover adheres with its breast edges projecting past the breast face of the heel. These projecting breast edges are then trimmed, deflected around the breast corners of the heel and applied to the breast face, to which they also adhere. Heretofore this operation has been performed mostly or entirely by hand and it is an object of the present invention to provide a machine which will facilitate the performance of certain of the steps in the operation, producing more uniform and accurate results at higher speed, and consequently at less cost, than are obtained by hand operation.

With the above stated and other objects in view an important feature of the invention resides in a blade having a cutting edge for trimming an edge of a heel cover and a cover engaging face for deflecting said edge around a corner of the heel, the term "corner" being used in the present specification and the following claims to denote the place or line of meeting of two intersecting faces of a heel. In the illustrated machine provision is also made for tucking the trimmed edge portion of the cover into a channel in the heel and in this connection invention is also to be recognized in the combination with means for de-

flecting a portion of a cover around a corner of a heel of means for tucking the cover material into a channel in the heel.

Another feature of the invention, contributing to speed and accuracy of production, consists in the combination of means for positioning a heel having a cover thereon with means for trimming simultaneously a plurality of edges of the cover. Similarly, the invention provides a further novel combination of means for positioning a channeled heel with means for tucking simultaneously a plurality of edges of a cover into a plurality of channels in the heel.

According to a further feature of the invention there is provided an upwardly facing tucking blade constructed and arranged to serve both as a positioning support for a channeled heel and as an instrument for tucking a portion of a cover into the channel in the heel. In the illustrated machine means is provided for transferring the positioned heel to the cover trimming mechanism and returning it to the tucking mechanism, which tucks the trimmed edge portions of the cover into the heel channels.

A still further advantageous feature of the invention consists in the provision of means for supporting a heel with a cover thereon with the heel breast facing downward and the breast edges of the cover depending beyond the heel breast, in combination with means for trimming said edges to a predetermined relation to the corners of the heel breast. In the embodiment of the invention herein shown the trimming mechanism includes shear couples which are arranged so to co-operate with the heel positioning and tucking mechanism that the edge portions of the heel cover will be trimmed accurately to exactly the proper width to permit them easily to be tucked smoothly and securely into the channels in the heel. Adjustments for the positioning, trimming and tucking instru-

mentalities are provided to secure accurate co-operation, to the end that perfection in the product may be secured.

These and various other features of improvement provided by the invention will be best understood and appreciated from the following detailed description of one embodiment thereof to be read in connection with the accompanying drawings, in which

10 Fig. 1 is a view in side elevation of a machine embodying the invention;

Fig. 2 is a front view of the machine;

Fig. 3 is a plan view.

15 Fig. 4 is a perspective view of the heel positioning and tucking devices;

Fig. 5 is a side elevation of the same showing the preliminary application of a heel cover;

20 Fig. 6 is a fragmentary view upon an enlarged scale showing the co-operation of the heel positioning and tucking devices with the heel channels and cover;

Fig. 8 illustrates the work in cover trimming position;

Figs. 9 and 10 show the heel being transferred from trimming to tucking position;

30 Fig. 11 shows a detail of an adjustment for the positioning and tucking devices; and

Fig. 12 is a perspective view of the product of the machine.

Referring to Figs. 1, 2 and 3, 20 indicates 35 a base upon which are uprights supporting bearings 22 in which is journaled a shaft 24 from which movement of the power driven parts of the machine is derived. Upon the shaft 24 is a worm gear 26 driven by a worm 40 28 which is operated by a motor 30 supported in a standard 32 arising from the base 20.

Pivoted upon stationary trunnions 34 are a pair of arms 36 upon the forward ends of which is mounted a support 38. Pivoted at 45 40 upon the support 38 are tucking blade carriers 42 which are geared together, as shown at 44, to cause them to move equally and oppositely about their pivots 40. The support 38 is provided with arcuate slots 46 through 50 which pass clamping screws 48 threaded into the respective carriers 42, providing for securing the carriers in any angular position to which they may be adjusted.

Tucking blades 50 are mounted upon the 55 carriers 42, being fixed in position by retaining blocks 52 secured by screws 54. The edge portions 56 (see Fig. 6) of the tucking blades 50 are thin while their base portions, in the region indicated by 58, are relatively 60 thick. As shown, the additional thickness is secured by the provision of an additional piece of metal 60 but this is solely for convenience in manufacture, and for the purposes of the invention the parts 56 and 60 65 should be regarded as integral, since they

are rigidly secured together and together form the tucking blade. In other words, the tucking blade might as well be formed of a single piece of material.

The inner portion of each of the carriers 42 forms, at 62, an abutment beside the tucking blade 50, said abutment being adapted to be engaged by a face of a channeled heel 64 at one side of the channel 66 which the tucking blade is to enter. The illustrated machine is designed to operate upon a heel having a channel in its breast face parallel and adjacent to each breast corner and it will be seen that the two upwardly facing tucking blades 50, with their adjacent abutments 62, afford means for positioning such a heel when the carriers 42 are properly adjusted upon the support 38 to cause the blades to conform to the channels in the heel.

Rigid with the arms 36 and extending rearwardly from the trunnions 34 is a cam lever 68 (see Figs. 1, 3 and 11) carrying a cam roll 70 which is freely rotatable upon a stud 72 which is eccentrically mounted in the lever 68 and held in adjusted position by a nut 74.

90 The roll 70 engages in a closed cam 76 the center line of which is indicated by the heavy dot and dash line 78 in Fig. 1. The cam 76 is secured to the shaft 24 and rotates therewith and is of such shape that the arms 36 are first lowered, held in lowered position for a time, then raised part way, held in this position for a time, and finally elevated to their initial position.

95 After a heel 64 has been positioned upon the tucking blades 50 and their abutments 62 it is seized by a clamp or holder comprising a pair of arms 80, 82 movable about a pivot 84 secured in stationary upright brackets 86. The arms 80, 82 are provided with roughened jaws 88, 90 arranged to engage the attaching face and the outer face respectively of the heel 64 and are normally held separated by an expansion spring 92 (Fig. 1) the ends of which are seated in pockets in the two arms.

100 For the purpose of closing the clamping jaws upon the heel there is provided a cam 94, pivoted at 96 in ears 98 which are rigid with the arm 82. Secured to the cam 94 is a handle 100 by which the clamp may be closed manually.

105 Co-operating with the cam 94 is a button 102 having a threaded stem 104 engaging a nut 106 which is splined in a housing 108 secured firmly to the clamp arm 80. A stiff spring 110 contained in the housing 108 is backed up by an adjustable screw 112 and bears against the nut 106, tending to force the latter against a stop plate 114 secured to the housing.

110 The tension upon the spring 110 is adjusted by means of the screw 112 to secure the clamping pressure desired, and the button 102 is so adjusted in the nut 106 that when the handle 100 is brought down to the posi- 115

tion shown in Fig. 1, wherein a stop pin 116 upon the cam 94 engages the clamp arm 82, the normal, stopped position of the heel to be operated upon will be seized, the heel clamp being open or closed, depending upon the position of the handle 100.

Adjustment of the button 102 is such that when the heel is clamped the nut 106 will move slightly away from the stop plate 114, the tucking blades 50, the breast face of the

An arm 118, which is rigidly secured to the heel adjacent to the channel resting upon the clamp arm 80, is connected by a link and positioning abutments 62. The turn buckle 120 to a rocker arm 122 upon a rock shaft 124 which also carries a cam lever 126 having at its end a cam roll 128 engaging the inner walls of the closed cam 130 rigidly mounted upon the shaft 24. The center line of the cam 130 is indicated by the heavy dot and dash line 132 in Fig. 1 and the function of this cam is to oscillate the heel clamp or holder 80, 82 as a whole about the pivot 84.

The positioned and clamped heel 64 with a cover 134 partially applied to it is to be subjected to a cover edge trimming operation and for this purpose the following mechanism is provided. A pair of normally stationary shear blades or cutters 136 are mounted upon supports 138 which are arranged for adjustment transversely of the machine in guides 140. Pins 142 depending from the supports 138 engage in eccentrically disposed slots 144 (Fig. 3) in a disk 146 provided with a handle 148 by which it may be rotated to adjust the shear blades 136 equally and oppositely toward or from each other. This movement of the blades 136 is one of adjustment only and does not occur in the normal operation of the machine upon the work.

Co-operating with the blades 136, to constitute a pair of shear couples, are horizontally movable shear blades or cutters 150 which are secured upon slides 152. Each of the slides 152 carries a cam roll 154 engaging a barrel cam 156 secured to the shaft 24, the cams 156 being symmetrical in respect to each other so that one revolution of the shaft 24 causes the movable shear blades 150 to be moved first toward and then away from the stationary shear blades 136.

The blades 150 are secured to the slides 152 by bolts 158 passing through slots in the blades and through slots in wedges 160 co-operating with corresponding wedge shaped formations 162 upon the slides. When the bolts 158, which are threaded into the slides 152, are loosened the blades 150 may be adjusted horizontally to compensate for grinding away of their edges in repeated sharpenings and may be adjusted vertically by means of screws 164 engaging the wedges 160, to cause the blades to co-operate accurately with the vertically stationary blades 136 to produce a clean shearing cut upon the heel cover.

The application of power to the shaft 24 from the motor 30 is determined by a conventional one revolution clutch controlled by a rod 168 (Fig. 1) which may be actuated by

Before the machine is started an adhesively coated cover 134 is drawn and stretched around the back and sides of the heel to which it immediately adheres, the breast edge portions of the cover projecting downward into space past the breast corners of the heel. The clutch is now tripped and one revolution of the shaft 24 occurs. First, the tucking blades 50 descend sufficiently to leave the channels 66 in the heel and to clear the projecting edge portions of the cover. The

clamp is next swung inward, transferring the applied cover, inward to trimming position above the shear couples. The shear couples being wide open, the depending untrimmed edge portions of the cover pass between the shear blades and the transferring movement of the heel holder ceases. The slides 152 then move inward, the upper faces of the cutters 150 engaging and functioning as means for deflecting the edge portions of the cover around the breast corners of the heel, after which the cutting edges of the blades 150, co-operating with the stationary blades 136, trim the said edge portions of the cover as shown in Fig. 8. The blades 150 are now retracted, leaving the trimmed edge portions of the cover deflected inward but not sufficiently to touch the breast face of the heel, to which they would adhere, making the subsequent tucking operation difficult.

During the retraction of the shear blades 150, or immediately thereafter, the tucking blades 50 are partially raised to a position such that the breast face of the heel, when it is again swung outward, will just clear them easily. The tucking blades remain in this position while the heel clamp swings outward to its initial position and stops.

During the outward transfer of the heel from trimming position to initial or tucking position the deflected edge portions of the cover, which are convergent because of the taper of the heel, engage the upper edges of the similarly convergent tucking blades 50, first passing outward between the blades and then being further deflected inwardly of the heel by passing over the blades, as shown in Fig. 10.

When the heel has come to rest the deflected, trimmed edge portions of the cover 134 rest upon the edges of the tucking blades and the channels 66 are exactly above the blades. Finally the support 38 is elevated to its initial position, causing the blades 50 to lay the trimmed edge portions of the heel cover upon the breast face of the heel between the channels 66 and the corners and tuck the cover into the channels, whereupon the machine stops. The clamp 80, 82 is now opened, releasing the heel, which is removed, and the machine is ready for the reception of the next heel to be operated upon.

The dimensions and conformation of the tucking tool 50, with its thin edge and relatively thick base portion, are determined by the dimensions of the channel in the heel to be operated upon and the thickness of the covering material to be used. The thickness of the base portion of the tucking tool approximates the difference between the width of the channel, and the thickness of the covering material and the width of the thin edge portion of the tool is at least as great as the difference between the depth and the width of the channel. Thus, while it is impossible for the edge portion of the cover material to be pinched or caught between the thick base portion of the tucking tool and the side of the channel in the heel, provided the cover has been trimmed to the proper width as shown in Fig. 6, in the early part of the tucking operation, yet when the thick base portion of the tool enters the channel in the heel the edge of the cover is smoothed and pressed firmly against the wall of the channel to which it will adhere, leaving adequate space in the channel for the subsequent tucking in of the edges of a breast cover.

Variation of the width of the edge portion of the cover left projecting past the breast face of the heel after the trimming operation, to suit the requirements of the heels being dealt with, is secured by adjustment of the normally stationary cutting blades 136, the further toward the center of the machine they are set the greater being the projection of the trimmed edge portion of the cover.

Having described the invention what is claimed as new and desired to be secured by Letters Patent is:

1. In a machine for use in covering heels, a blade having a cutting edge for trimming an edge of a cover, and a cover engaging face

for deflecting said edge around a corner of a heel.

2. In a machine for use in covering heels, the combination of means for trimming an edge of a cover and means for tucking the trimmed edge into a channel in a heel. 70

3. In a machine for use in covering heels, the combination of a cover edge trimming cutter and a tucking blade operable to tuck a trimmed edge of a cover into a channel in a heel. 75

4. In a machine for use in covering heels, the combination of a cover edge trimming cutter, a movable tucking blade, and power operated mechanism for operating the cutter and the tucking blade automatically in succession to trim an edge of a heel cover and tuck the trimmed edge into a channel in a heel. 80

5. In a machine for use in covering heels, the combination of means for trimming an edge of a cover, means for deflecting said edge around a corner of the heel, and means for tucking the trimmed edge into a channel 85 90 in the heel.

6. In a machine for use in covering heels, the combination of a cover edge trimming cutter having a cover deflecting face, and a power operated tucker for tucking a trimmed and deflected edge of a cover into a channel in a heel. 95

7. In a machine for use in covering heels, the combination of means for deflecting a portion of a cover around a corner of a heel and means for tucking the cover material 100 into a channel in the heel.

8. In a machine for use in covering heels, the combination of means for trimming an edge of a cover upon a heel, means for securing the trimmed edge portion of the cover to the heel, and means for transferring the heel and cover from the trimming means to the securing means. 105

9. In a machine for use in covering heels, the combination of means for trimming an edge of a cover upon a heel, means for tucking the trimmed edge of the cover into a channel in the heel, and means for transferring the heel and cover from the trimming means to the tucking means. 110 115

10. In a machine for use in covering heels, the combination of a shear couple, a movable tucking blade, a heel holder movable between the shear couple and the tucking blade, and power operated mechanism for operating the shear couple, moving the heel holder, and operating the tucking blade, automatically in succession. 120

11. In a machine for use in covering heels, the combination of means for trimming an edge of a heel cover, means for deflecting a portion of the cover around the corner of a heel, and means for tucking the trimmed edge of the cover into a channel in the heel. 125

12. In a machine for use in covering heels, 130

- the combination of means for positioning a heel having a cover thereon, and means for trimming simultaneously a plurality of edges of the cover.
5. 13. In a machine for use in covering heels, the combination of a holder for a heel having a cover thereon, and a plurality of shear couples operable simultaneously to trim a plurality of edges of the cover.
10. 14. In a machine for use in covering heels, the combination of means for positioning a channeled heel, and means for tucking simultaneously a plurality of edges of a cover into a plurality of channels in the heel.
15. 15. In a machine for use in covering heels, the combination of a holder for a heel having a cover thereon, a pair of tucking blades, and power means for effecting relative approaching movement of the holder and blades to cause the blades simultaneously to tuck two edges of the cover into channels in a heel in the holder.
20. 16. In a machine for use in covering heels, the combination of means for supporting a heel with a cover thereon with the heel breast facing downward and an edge of the cover depending beyond the heel breast, and means for trimming said edge to a predetermined relation to the corners of the heel breast.
25. 17. In a machine for use in covering heels, the combination of means for supporting a heel with a cover thereon with the heel breast facing downward and the breast edges of the cover depending beyond the heel breast, and means for simultaneously trimming said edges to a predetermined relation to the corners of the heel breast.
30. 18. In a machine for use in covering heels, an upwardly facing tucking blade constructed and arranged to serve both as a positioning support for a channeled heel and as an instrument for tucking a portion of a cover into the channel in the heel.
35. 19. A tucking tool for use on channeled heels, comprising a tucking blade adapted to tuck covering material into a channel in a heel, and an abutment adapted to engage a face of the heel beside the channel, to determine the depth to which the blade may enter the channel.
40. 20. A tucking tool for use on channeled heels, comprising a tucking blade adapted to tuck covering material into a channel in a heel, and an abutment adapted to engage a face of the heel beside the channel to determine the depth to which the blade may enter the channel, said blade being thicker at its base than at its edge.
45. 21. A tucking tool for use in tucking covering material of predetermined thickness into a channel of predetermined width and greater depth, said tool having a base portion of a thickness approximating the difference between the width of the channel and the thickness of the covering material, and a relatively thin edge portion of a width at least as great as the difference between the depth and the width of the channel.
50. 22. In a machine for use in covering heels, a tucking blade, means associated with the blade for positioning a channeled heel thereon, means for trimming an edge of a cover upon the heel, and means for varying the position of the tucking blade and positioning means relatively to the trimming means.
55. 23. In a machine for use in covering heels, a tucking blade, means associated with the blade for positioning a channeled heel thereon, means for deflecting a portion of a cover around a corner of the heel, and means for varying the position of the tucking blade and positioning means relatively to the deflecting means.
60. 24. In a machine for use in covering heels, a pair of convergent tucking blades arranged to tuck the edges of a cover into correspondingly convergent channels in a heel, means for deflecting portions of a cover around the corners of a heel, means for effecting relative movement of the blades and heel longitudinally of the blades with the heel close to the edges of the blades and the deflected portions of the cover between the blades, and means for effecting relative approaching movement of the blades and heel to tuck the deflected portions of the cover into the channels in the heel.
65. 25. In a machine for use in covering heels, the combination of tucking blades, means associated with said blades for positioning a channeled heel thereon, a movable clamp adapted to seize the positioned heel, and means for removing the tucking blades from the clamped heel to permit the clamp to transfer it to another position for an operation upon it.
70. 26. In a machine for use in covering heels, the combination of tucking blades, means associated with said blades for positioning a channeled heel thereon, a movable clamp adapted to seize the positioned heel, mechanism for trimming a cover upon the heel, means for moving the clamp to transfer the clamped heel from tucking position to trimming position and back, and means for moving the tucking blades away from the heel before it is transferred away from tucking position and toward the heel to tuck the trimmed cover in the channels after the heel is returned to tucking position.
75. 27. In a machine for use in covering heels, the combination of a pair of normally stationary shear blades and a pair of shear blades movable in the same plane, constituting two shear couples, means for positioning a heel at one side of the plane of said shear couples with untrimmed edge portions of a partially applied heel cover projecting between the blades of the respective couples, and means for varying in said plane the posi-

tions of the normally fixed blades to determine the width of the trimmed edge portions of the cover which will be produced when the shears are operated.

- 5 28. In a machine for use in covering heels, the combination of a shear couple operable in one plane, said couple comprising a pair of shear blades one of which is adjustable relatively to the other in a direction normal to said plane to secure co-operation between the cutting edges of the blades, a clamp constructed and arranged to hold a heel adjacent to said shear couple with an untrimmed edge portion of a partially applied heel cover projecting between the blades thereof, and a positioning device adjustable in a direction substantially normal to said plane for determining the position of the heel in the clamp.
- 10
